UNITED STATES PATENT OFFICE.

GEORGE C. HESTER, OF CHICAGO, ILLINOIS, ASSIGNOR TO BRASCO MANUFACTURING COMPANY, OF CHICAGO, ILLINOIS, A CORPORATION OF ILLINOIS.

STORE-FRONT CONSTRUCTION.

1,263,245.

Specification of Letters Patent. Patented Apr. 16, 1913.

Application filed May 23, 1914. Serial No. 840,596.

To all whom it may concern:

Be it known that I, GEORGE C. HESTER, of Chicago, in the county of Cook, and in the State of Illinois, have invented a certain 5 new and useful Improvement in Store-Front Constructions, and do hereby declare that the following is a full, clear, and exact description thereof.

Sashes of sheet metal, such, for example, 10 as copper, are largely used for store front construction where large sheets of plate glass are used, the sheet metal being desirable because of the attractive finish to the window it presents, its inexpensiveness of manufacture and the possibility of the 15 application of a metal surface to the glass without the intervention of putty between the contiguous surfaces of glass and sash. There are certain practical objections to 20 sheet metal sashes, such as are now used, some of which will be mentioned. The members of the sash as sold by the manufacturer and delivered to the job are mere shells of sheet metal and these members may be of consider- 25 able length. Obviously, in the handling of these shells they may be bent, or dented so that the appearance will be marred. Again, an all metal setting for plate glass is charged a higher rate of insurance than 30 a setting of wood because of the greater danger of breakage. It is important, for reasons well known to those skilled in the art, to provide for the drainage of water through the sash and for ventilation. The object of 35 my invention is to provide a store front construction which will possess all the advantages of the sheet metal finish, but without its drawbacks and having provision for drainage and ventilation, and to this end 40 my invention consists in the store front constructed substantially as hereinafter specified and claimed.

In the accompanying drawings—

Figure 1 is a perspective view of a portion 45 of a sash bar embodying my invention;

Fig. 2 is a vertical section through the sash at bottom, top or head and the transom bar;

Fig. 3 is a horizontal section through one 50 of the side jambs.

In the main, or principally, my sash comprises two members or moldings between which the margin, or edge of the plate of glass is clamped, one of which members 55 supports the latter at its bottom edge and at

the inner side of the glass provides a gutter to receive water of condensation, or wash water flowing down the inner side of the glass and from which gutter it is discharged through suitable passages or openings also 60 serving as air passages for ventilation. Each of these members consists of a strip of wood or other material having the characteristics of wood which fit it for this purpose and a sheet metal covering, or facing 65 for the strip which covers and conceals all the surfaces that would be exposed to view so that the appearance is that of metal construction, and so that the surfaces of the strip, which otherwise water might have access to, will be protected and danger of rotting or other deleterious action on the wood or other material from the action of water is avoided. One of these members or moldings is designated A in the drawings and the 70 other is designated B. I shall describe these members for convenience as made of strips of wood; but it will be understood that when I use the term "wood" I mean any material having the characteristics of wood which 75 peculiarly fit it for the use in question such characteristics being sufficient yieldability not to endanger the glass by its clamping action and so as to be in effect a cushioned support and sufficient substance or body as 80 to provide all required anchorage or support which the large plates of glass that are used require. Wood is also desirable because of its lightness and inexpensiveness and the facility with which it can be given 85 the desired shape and the sheet metal covering applied thereto.

The member A is the inner glass-engaging strip and is used at the sill or bottom of the window, and on the upper side of the 90 transom bar C so as to be at the bottom of the plate of glass above the transom bar and may be used at the underside of the transom bar and at the underside of the head, although, as indicated in Fig. 2 of 100 the drawing, the strip B, which primarily is the outer glass-engaging strip may also be used at the inner side of the glass at the head jamb and also as shown in Fig. 3, at the inner side of the side jamb. The outer, 105 or exposed surface of the inner strip A is formed into a valley by inclinations from each of its opposite edges so as to provide a gutter for wash water, or water of condensation when the strip is at the bottom of the 110

plate of glass and such surface is covered for proper protection by sheet metal, such as copper in the form of a strip 10 which is carried over the gutter-forming surfaces 5 and at the edge or side next to the glass is carried downward a short distance and its edge placed in a kerf, or slit in the front side of the strip and at the rear the strip of sheet metal is carried downward or over the 10 rear or inner side of the strip and thence inward a short distance and its edge similarly carried into a kerf in the wooden core of the strip. The outer, or otherwise exposed surfaces of the outer clamping strip 15 B are also covered by sheet metal, such as copper, and the edges of the sheet, or strip of copper are likewise carried into kerfs in the wooden strip, as clearly indicated in the drawings.

20 In the case of the sill or transom bar the upper surface thereof beneath the glass and also the outer face are covered by a sheet metal facing, or cover 11, which is preferably of copper and to provide for the passage 25 of water and the circulation of air beneath the plate of glass the horizontal portion of the covering is embossed to form hollow ribs or corrugations 12 at intervals beneath the bottom of the plate of glass and channels, or depressions 13 at intervals beneath the outer clamping strip B the latter resting at its bottom upon the embossed or raised portions, or hollow ribs 12 that are separated by said depression. The covering 30 11 at its inner edge at a position inside of the vertical plane of the inner face of the plate of glass has a vertical flange against which abuts the front side of the inner clamping strip A so that it constitutes an inner metal wall of the gutter directly beneath the bottom of the glass plate and into which gutter, water is discharged from the valley, or 35 gutter in the upper side of the inner strip A through downwardly and forwardly inclined holes 15 in said inner clamping strip, said holes being lined with metal tubes 16, or otherwise treated to render the walls of wood impervious to moisture, and said tubes extend sufficiently far beyond the wooden 40 strip to make certain of the discharge of the water into said lower gutter. The corner of both the inner and outer clamping strips A and B, contiguous to the glass, and at the bottom is cut away to form a channel, or recess 45 17 extending lengthwise of the strip to provide a space or chamber of ample capacity above the lower gutter so that room or space is afforded in which any water in the gutter that freezes may expand during 50 freezing without affecting the setting. The presence of these channels in providing an enlarged air space also contributes to the rapid evaporation of moisture by reason of the large volume of air that exists at such 55 point and its free circulation through the

setting. The vertical lip, or flange 18 of the covering 11 is also useful as forming a gage or stop for setting the inner glass-engaging molding A, and thus fixing exactly the proper position of the plate of glass. The 70 inner strip A is first secured in position, as by means of screws 19 which pass through it into a contiguous portion of the wood work and afterward the outer strip B is applied, and such inward adjustment as is 75 necessary being arranged for by using securing screws 20 which pass through said retaining strip downward and inward, and by reason of their inclination cause an inward clamping action of the outer strip 80 against the glass.

Under the inner side of the head, the transom bar and the side jamb have a sheet metal covering 22, preferably of copper, which has at its inner edge a lip or flange 85 23 which corresponds to the lip or flange of the lower gutter, and it is useful, as providing a stop or gage in setting the inner glass-engaging strip whatever its form may be.

It will be understood that no drainage 90 holes are required in the head and side jamb glass-engaging strips, or the under transom bar-engaging strips, but if they are desired for ventilation and they may easily be provided and if preferred may be lined 95 with metal tubes just as in the case of the inner glass-engaging strip at the bottom of the plate of glass.

It will be seen that my construction possesses all the characteristics necessary to 100 achieve the object that I have had in view and it has the advantages of simplicity of manufacture and installation and of excellent looks or appearance when installed, for both inside and outside the clamping strips 105 have a substantial, yet graceful appearance.

Having thus described my invention what I claim is—

1. As an improvement in store front construction, a sash having inner and outer 110 glass-engaging moldings consisting each of a strip of wood having its exposed surfaces covered with sheet metal, each strip at its bottom and next to the glass having a portion removed to provide a longitudinally extending channel at the bottom of the glass, said channels being in communication beneath the glass and means establishing communication between said channels and the space above the inner molding in 120 rear of the glass, and between said channels and the space outside the glass, and providing a direct passage between the inner and the outer sides of the glass.

2. As an improvement in store front construction, a sash having inner and outer 125 glass-engaging moldings consisting each of a strip of wood having its exposed surfaces covered with sheet metal, each strip at its bottom and next to the glass having a por- 130

tion removed to provide a longitudinally extending channel at the bottom of the glass, said channels being in communication beneath the glass, means establishing communication between said channels and the space above the inner molding in rear of the glass, and between said channels and the space outside the glass and providing a direct passage between the inner and the outer sides 10 of the glass, and a metal member spaced below the bottom of the glass and having a vertical wall in rear of the point of communication between the space below the glass and the space in rear of the glass above the 15 inner strip.

3. As an improvement in store front construction, a sash having inner and outer glass-engaging moldings, consisting each of a strip of wood having its exposed surfaces

covered with sheet metal, the top of the inner molding constituting a gutter, a tube passing through the inner molding leading from said gutter downward to a space between the moldings, and a metal member situated beneath the glass and beneath the outer moldings and having in rear of the lower end of the opening a vertical wall, each of said wood strips having at its lower inner corner a longitudinally extending channel, or recess to provide an open space, 30 said tube having its lower end in advance of said vertical wall.

In testimony that I claim the foregoing I have hereunto set my hand.

GEORGE C. HESTER.
